(57) **CLAIM**

The ornamental design for the lower back portion of a golf iron, as shown and described.

DESCRIPTION

FIG. 1 is a perspective view of a design for a fragmentary portion of the lower back portion of a golf iron;

FIG. 2 is a rear elevation of the design shown in FIG. 1;

FIG. 3 is a toe elevation of the design shown in FIG. 2;

FIG. 4 is a planar cross-section taken along lines 4—4 in FIG. 2;

FIG. 5 is a planar cross-section taken along lines 5—5 in FIG. 2; and,

FIG. 6 is a planar cross-section taken along lines 6—6 in FIG. 2.

The broken line showing is included for the purpose of illustrating and forms no part of the claimed design.
